HAIR CURLING DEVICE

Harry Klein, New York, N. Y.

Application December 21, 1938, Serial No. 247,010.

24 Claims. (Cl. 132—33)

My invention relates to a new and improved construction for hair curling devices.

One of the objects of my invention is to provide an improved hair curling device of the character described provided with novel means for mounting and manipulating a hair gripping member.

Another object of my invention is to provide an improved hair curling device of the character described adapted for use in connection with a hair pin and having highly improved means for temporarily mounting such hair pin.

Still another object of my invention is to provide an improved hair curler device of the character described which shall comprise relatively few and simple parts, which shall be easy to assemble, which shall be relatively inexpensive to manufacture, and which at the same time shall operate with a high degree of efficiency.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawing, in which is shown one of the various possible embodiments of this invention,

Fig. 1 is a longitudinal cross-sectional view of a hair curler device constructed in accordance with my invention;

Fig. 1a is a sectional view taken along the line I—I of Fig. 1;

Fig. 2 is a top plan elevational view of the Fig. 1 form of device;

Fig. 3 is a side elevational view thereof illustrating one step in the operation of the device;

Fig. 4 is a top plan elevational view illustrating still another step in the operation of my device;

Fig. 5 is a fragmentary view of a portion of the device shown in Fig. 1 but illustrating a modified form of hair pin mounting means;

Fig. 6 is a view similar to the Fig. 1 form of device but illustrating a modified form of hair gripping assembly; and

Fig. 7 is an elevational view, partly sectional, of the curler device shown in Figs. 1 to 4 but illustrating still another modified form of construction.

Referring now in detail to the drawing, I have disclosed in Figs. 1 to 4 a hair curling device constructed in accordance with my invention and comprising a curler rod 10, at one end of which

there is fixed a finger gripping member 11 which may be of larger diameter than said curler rod or smaller diameter and which may have the outer surface thereof knurled, as shown. The curler rod 10 and finger gripping member 11 may be held in assembled relationship by any suitable means such as, for example, a portion 10a adjacent one end of the curler rod 10 being received in a corresponding opening 11a in the finger gripping member 11 by means of a force fit. For the purpose of gripping the end of a lock of hair which is to be wound on the curler rod 10, there is provided a hair gripping member 12 having a main gripping portion 12a and an offset portion 12b parallel to the portion 12a and interconnected by a portion 12c. The gripping member 12 is designed so that the main gripping portion 12a is substantially parallel to the curler rod 10 and is so mounted that it will maintain its parallel relationship thereto even when moved away from the curler rod 10 for the purpose of inserting a lock of hair therebetween. By this parallel construction the lock of hair is gripped uniformly throughout. Also the freedom with which the wound curl may ultimately be slidably moved off the curler rod is greatly increased.

For causing the gripping portion 12a to move relative to the curler rod 10, there is provided a button member 14 slidably movable in an opening 15 in the member 11. The button 14 is provided with a transverse opening 16 into which the portion 12b of the gripping member 12 is received. A spring 17, one end of which bears against the wall of the opening 15 and the other end of which bears against the bottom wall of a cupped portion 18 of the button 14, serves to normally urge the gripping arm 12a into contractive engagement with the curler rod. An inwardly extending slot 19 is provided adjacent one end of the member 11 to permit the free movement of the gripping member portions 12b and 12c therein when the button 14 is manually moved. It is noted that the gripping arm 12a in all its positions, whether in the full line hair gripping position as shown in Fig. 1 or whether in the dotted line position 12a', always maintains its parallelism with the curler rod 10. By the above-described construction, it is seen that undesirable pinching of that portion of the lock of hair gripped adjacent the junction of the curler rod 10 and the member 11 is avoided. To obtain a more positive gripping action between the hair gripping member 12 and the curler rod 10, the said curler rod 10 is provided with a recessed

portion 29 into which the arm portion 12a is partially received.

The free end 10b of the curler rod 10 is constructed as follows for the purpose of efficiently holding the hair pin 20 until the lock of hair has been spirally wound on the curler rod 10, after which the said curled lock of hair may be relatively slidably moved toward the free end 10b of the curler rod so that the curl of hair may be received between the legs of the hair pin 20 which will clamp the same and hold the curl in wound condition. The curler rod 10 is provided with an opening 21 extending inwardly from the free end thereof. Into this opening 21 there is placed a cylindrical member 22 rotatable relatively to said curler rod and having an opening 23 extending inwardly from the outer end thereof. Disposed within said opening 23 and substantially centrally thereof is a projecting pin 24 providing a space between the outer surface of said pin 24 and the wall of the opening 23. The pin 24 which may be integral with the member 22 is preferably provided with a tapered point 25 for reasons which will soon become apparent. A plug 26 is forcibly fitted into the end 10b of the curler rod 10 to close the opening 21, the said plug being provided with a through aperture 27 in substantially axial alignment with the projecting member 24. The hair pin 20, which may be of any suitable type well known to the art, is adapted to have one leg 20a thereof inserted through the plug aperture 27, and due to the tapered point 25, will be deflected to one side of the projecting member 24 so that it will be obliged to enter the space 23 surrounding the member 24 to be wedged therebetween and frictionally held in position. Thus, the hair pin will be prevented from falling out during the curling operation. Also sufficient additional friction is thus provided to enable the hair pin 20 to remain in position until the wound curl has been removed from the curler rod 10. The plug member 26 is provided with a tapered outer surface 26a which will cause the leg 20b of the hair pin 20 to spread apart with respect to the leg 20a. The opening 23 in the member 22 is designed with respect to the end of the curler rod and to the legs of the hair pin 20 so that the said hair pin 20 will be prevented from insertion into said opening 23 to such a depth as to interfere with the lateral or turning movement of the gripping arm 12a or of the wound curl of hair.

While in the drawing I have illustrated the projecting member 24 as being a part of a separate rotatable cylinder 22, it is understood that the said projecting member may be attached directly to or may be an integral part of the curler rod 10.

The operation of my improved curler device will now be described: One leg of a hair pin 20 is inserted in the end 10b of the curler rod 10 through the openings 27 and 23 and frictionally held in position as above described. The push button member 14 is slidably moved inwardly of the member 11 against the action of the spring 17, which will cause the arm 12a to be raised to the dotted line position 12a' (see Fig. 1). The end of a lock of hair to be curled is then positioned between the arm 12a and the curler rod 10, after which the push button 14 is released and, due to the action of the spring 17, the arm 12a will grip the said lock of hair. Next, the fingers of one hand of the operator hold the projecting portion of the hair pin 20 to maintain the same stationary, while with the other hand,

the operator grasps the finger gripping member 11 and turns the same, causing rotation of the curler rod 10 and the gripping arm 12a in a direction toward the scalp S to spirally wind the lock of hair. After a curl of desired size is achieved, the gripping arm 12a is raised to the dotted line position 12a' as hereinbefore described and the curl is then slidably moved relative to the curler rod 10 in a direction toward the hair pin 20 so that ultimately the leg 20b of the hair pin 20 will be disposed adjacent the outside surface of the wound curl while the leg 20a will be disposed on the inside surface of the said wound curl. The curler rod is entirely withdrawn and the curl is then maintained in its wound condition by means of the hair pin.

In Fig. 5 I have shown a modified form of my invention directed to the means for retaining the hair pin 20 against accidentally jumping out during the operation of the device. In this form a plug member 26' is employed in the opening 21 of the curler rod 10' similar to the member 26 but, instead of the projecting member 24, there is provided a tubular member 30 of wavy cross-sectional contour in a longitudinal direction as shown. One end of the tube 30 is freely and rotatably held by the plug member 26' while the opposite end of said member 30 is freely and rotatably held in a recessed portion of the curler rod 10' adjacent the opening 21. An opening 31 in axial alignment with the opening 21' is provided in the tubular member 10'. It is noted from the above described construction that, when the leg 20a of the hair pin is inserted through the opening 27', it will pass through the tube 30 and into the opening 31. Due to the wavy longitudinal contour of the member 30, it is noted that the hair pin 20 will be prevented from accidentally slipping out of position during the curling operation. In this form of construction it is noted that when the curling pin 20 is held stationary while the curler rod 10' is rotated, the tube 30 will also be held stationary and the said curler rod 10' will rotate with respect thereto.

In Fig. 7 there is shown a simple form of retaining means for the hair pin 20. In this case, the curler rod 40 is provided adjacent the free end thereof with a relatively narrow axial opening 41 into which one leg 20a of the pin 20 is received, and the inherent resilient wavy contour of the hair pin will hold it within the opening 41.

In the forms of my invention for retaining the hair pin 20 in position, as above described, it is noted that the distance to which the hair pin leg 20a is inserted in the curler rod 10 is limited, so that both hair pin legs 20a and 20b will terminate at a spaced distance from the free end of the gripping arm 12a so that the hair which is wound on the curler rod 10 will not come into contact with or be interfered with by the hair pin 20 during the winding operation.

In Fig. 6 I have shown a modified form of my invention. In this form, the hair gripping member comprises a rod 50 having a slightly enlarged head portion 50a at one end thereof which is received in a socket opening 51 in the finger gripping member 52. Communicating with the opening 51 is a longitudinally disposed opening 53 having an enlarged portion 53a to permit freedom of pivotal movement of the member 50 about the head 50a which serves as a pivot. A threaded plug member 54 mounted in the member 52 serves to retain the gripping arm head 50a in the socket 51. The finger gripping member 52 is provided with an opening 55 into which there is slidably

mounted a plunger member 56 having a transverse opening 57 adjacent one end thereof in substantial axial alignment with the openings 53 and 53a and through which a portion of the gripping member 50 passes. It is thus seen from the above described construction that when the plunger member 56 is moved inwardly, the member 50 will be caused to pivotally move about its axis 50a to permit a strand of hair to be gripped between the member 50 and the curler rod 10. To normally maintain the gripping member 50 in contactive engagement with the curler rod 10, a spring 60 encircling the member 56 and disposed in the opening 55 is provided. In order to raise the gripping arm 50 for the purpose of gripping a lock of hair, it is merely necessary to push inwardly on the member 56 against the action of the spring 60 and upon release of the member 56, the lock of hair will be gripped preparatory to curling.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. In a hair curling device, a curler member adapted to have a lock of hair wound thereon, a finger gripping member attached to said curler member, a hair gripping member and means for mounting said hair gripping member on said finger gripping member for relative movement thereto, said hair gripping member comprising a portion thereof disposed within said finger gripping member and a portion thereof projecting outwardly from said finger gripping member.

2. In a hair curling device, a curler member adapted to have a lock of hair wound thereon, a finger gripping member attached to said curler member, a hair gripping member comprising a portion disposed inwardly of said finger gripping member and a portion projecting outwardly of said finger gripping member, said outwardly projecting portion being substantially parallel to said curler member, and means for resiliently urging said outwardly projecting hair gripping portion into contactive engagement with said curler member.

3. In a hair curling device, a curler member adapted to have a lock of hair wound thereon, a finger gripping member attached to said curler member, a hair gripping member comprising a portion disposed inwardly of said finger gripping member and a portion projecting outwardly of said finger gripping member, said outwardly projecting portion being substantially parallel to said curler member, and means for resiliently urging said outwardly projecting portion into contactive engagement with said curler member, said last named means comprising a spring mounted within said finger gripping member.

4. In a hair curling device, a curler member adapted to have a lock of hair wound thereon, a finger gripping member attached to said curler member, a hair gripping member comprising a portion disposed inwardly of said finger gripping member and a portion projecting outwardly of said finger gripping member, said outwardly pro-

jecting portion being substantially parallel to said curler member, means for resiliently urging said outwardly projecting portion into contactive engagement with said curler member, said last named means comprising a spring mounted within said finger gripping member, and manually manipulative means carried by said finger gripping member for causing said outwardly projecting portion to move out of contactive engagement with said first curler against the action of said spring.

5. In a hair curling device, a curler member adapted to have a lock of hair wound thereon, a finger gripping member attached to said curler member, a hair gripping member comprising a portion disposed inwardly of said finger gripping member and a portion projecting outwardly of said finger gripping member, said outwardly projecting portion being substantially parallel to said curler member, means for resiliently urging said outwardly projecting portion into contactive engagement with said first curler, said last named means comprising a spring mounted within said finger gripping member, and manually manipulative means carried by said finger gripping member for causing said outwardly projecting portion to move out of contactive engagement with said first curler against the action of said spring, said finger gripping member being so constructed and arranged that said outwardly projecting portion will maintain its parallelism with respect to said curler member during such movement.

6. In a hair curling device, a curler member adapted to have a lock of hair wound thereon, said curler member having a finger gripping portion, a hair gripping member comprising a portion thereof disposed substantially parallel to said curler member and means for moving said hair gripping member with respect to said curler member, said last named means including means for maintaining the parallelism between said hair gripping member portion and said curler member during such movement.

7. In a hair curling device, a curler member adapted to have a lock of hair wound thereon, a finger gripping member attached to said curler member, a hair gripping member cooperating with said curler member and attached at one end thereof to said finger gripping member, and means comprising a manually movable member for causing movement of said hair gripping member with respect to said curler member, said last named manually movable member being so arranged as to move in the same direction as said hair gripping member.

8. In a hair curling device, a curler member adapted to have a lock of hair wound thereon, a finger gripping member attached to said curler member, a hair gripping member and means for mounting said hair gripping member on said finger gripping member for movement relative thereto, said means comprising an actuating member slidably received in said finger gripping member and shiftable transversely of the longitudinal axis thereof, said curler member, said finger gripping member and said hair gripping member being turnable as a unit.

9. In a hair curling device, a curler member adapted to have a lock of hair wound thereon, a finger gripping member attached to said curler member, a hair gripping member, and means for mounting said hair gripping member on said finger gripping member for movement relative thereto, said last named means comprising a

button projecting from said finger gripping member and shiftable perpendicular to the longitudinal axis thereof, said curler member, said finger gripping member and said hair gripping member being turnable as a unit.

10. In a hair curling device, a curler member adapted to have a lock of hair wound thereon, a finger gripping member attached to said curler member, a hair gripping member pivotally mounted directly on said finger gripping member, and means carried by said finger gripping member for causing pivotal movement of said hair gripping member relative to said finger gripping member, said last named means comprising a button projecting from said finger gripping member and shiftable perpendicular to the longitudinal axis thereof.

11. In a hair curling device, a curler member adapted to have a lock of hair wound thereon, a hair gripping member comprising a portion substantially parallel to said curler member, means for resiliently urging said parallel portion into contactive engagement with said curler member, and manually manipulative means for causing said parallel portion to move out of contactive engagement with said curler member against the action of said resilient means, said hair gripping member being so constructed and arranged that said parallel portion will maintain its parallelism with respect to said curler during such movement.

12. In a hair curling device adapted for use with a hair pin, a curler member adapted to have a lock of hair wound thereon, an inwardly extending opening in one end of said curler member adapted to receive one leg of said hair pin therein and to leave the other end of said hair pin free, means to angularly spread the legs of said hair pin, and means freely rotatably mounted in said curler member wholly within said opening to frictionally grip the leg of said hair pin disposed in said curler member independently of any gripping effect caused by said spreading means.

13. In a hair curling device adapted for use with a hair pin, a curler member adapted to have a lock of hair wound thereon, an inwardly extending opening in one end of said curler member adapted to receive one leg of said hair pin therein and to leave the other end of said hair pin free, means to angularly spread the legs of said hair pin, and means freely rotatably mounted in said curler member wholly within said opening to frictionally grip the leg of said hair pin disposed in said curler member independently of any gripping effect caused by said spreading means, said last named means comprising a tubular member whose opening is in axial alignment with the opening in said curler member.

14. In a hair curling device adapted for use with a hair pin, a curler member adapted to have a lock of hair wound thereon, an inwardly extending opening in one end of said curler member adapted to receive one leg of said hair pin therein and to leave the other end of said hair pin free, means to angularly spread the legs of said hair pin, and means freely rotatably mounted in said curler member wholly within said opening to frictionally grip the leg of said hair pin disposed in said curler member independently of any gripping effect caused by said spreading means, said last named means comprising a tubular member whose opening is in axial alignment with the opening in said curler

member, said tubular member being of wavy longitudinal cross-sectional contour.

15. In a hair curling device adapted for use with a hair pin, a curler member adapted to have a lock of hair wound thereon, an inwardly extending opening in one end of said curler member adapted to receive one leg of said hair pin therein and to leave the other end of said hair pin free, means to angularly spread the legs of said hair pin, and means freely rotatably mounted in said curler member wholly within said opening to frictionally grip the leg of said hair pin disposed in said curler member independently of any gripping effect caused by said spreading means, said last named means comprising a tubular member whose opening is in axial alignment with the opening in said curler member, said tubular member having an axially located shaft disposed therein and spaced from the walls of said tubular member, said shaft being mounted in cantilever fashion at one end of said tubular member, the free end of said shaft facing the open end of said curler member.

16. A hair curler device including an elongated hair curler means presenting an external peripheral hair curling surface, a hair retaining member associated with said curler means and adapted to overlie said peripheral surface, means at one extremity of said elongated hair curler means for impositively accommodating one leg of a conventional spread hair clip with the open extremity of said clip positioned in alignment with said peripheral hair curling surface, said last named means comprising a member disposed internally within the elongated hair curler means and having an outer surface spaced inwardly from an inner wall of the hair curler means to provide a recess extending axially thereof for receiving the extremity of said leg and disposing said extremity fixedly in said recess when operatively received thereby, said hair curler means being apertured at a point spaced axially from said recess, said aperture being laterally disaligned with respect to said recess for laterally flexing said leg to impose a substantial resistance to withdrawal.

17. A hair curler device as defined in the claim preceding wherein said means for accommodating one leg of a conventional spread hair clip includes a peripheral outer surface for engaging the other leg of said hair clip and disposing it in inclined relation to said surface.

18. A hair curler device including an elongated hair curler means presenting an external peripheral hair curling surface, means at one extremity of said elongated hair curler means for impositively accommodating one leg of a conventional spread hair clip with the open extremity of said clip positioned in alignment with said peripheral hair curling surface, said last named means comprising a member disposed internally within the elongated hair curler means and having a surface spaced from an inner wall of the hair curler means to provide a recess extending axially thereof for receiving the extremity of said leg and disposing said extremity fixedly in said recess when operatively received thereby, said hair curler means being apertured at a point spaced axially from said recess, said aperture being laterally disaligned with respect to said recess for laterally flexing said leg to impose a substantial resistance to withdrawal.

19. A hair curler device as defined in the claim preceding wherein the surface of said internally disposed member comprises an outer cylindrical

surface coaxial with the elongated hair curler means and spaced inwardly from an inner annular wall of the hair curler means to provide an annular recess adjacent said wall.

20. A hair curler device including an elongated hair curler means presenting an external peripheral hair curling surface, means at one extremity of said elongated hair curler means for impositively accommodating one leg of a conventional spread hair clip with the other leg of said clip received on the outer surface of said device, said last named means comprising a hollow member supported internally of said hair curler means and a second member disposed internally of said hollow member and having a surface spaced from an inner wall of said hollow member to provide a recess extending axially of said hair curler means for receiving the extremity of said first leg and disposing said leg extremity fixedly in said recess when operatively received thereby, said hair curler device being apertured at one extremity at a point spaced axially from said recess, said aperture being laterally disaligned with respect to said recess for laterally flexing said leg to impose a substantial resistance to withdrawal.

21. A hair curler device as defined in the claim preceding wherein the hollow member is rotatably supported internally of the hair curler means.

22. In a hair curling device adapted for use with a hair pin, a curler member adapted to have a lock of hair wound thereon, an inwardly extending opening in one end of said curler member adapted to receive one leg of said hair pin therein and to leave the other leg of said hair pin free, means to angularly spread the legs of said hair pin, and means wholly within said opening to frictionally grip the leg of said hair pin disposed in said curler member independently of any gripping effect caused by said spreading means.

23. In a hair curling device, a curler member adapted to have a lock of hair wound thereon, and a spread hair pin supported at one end thereof, with one leg of the pin impositively accommodated in said member and the other leg over the external surface of said member, said member having an internal recess adjacent an end thereof which extends axially of said member for receiving the extremity of said first named hair pin leg and disposing said extremity fixedly in said recess when operatively received thereby, said hair curler means being apertured at a point spaced axially from said recess to permit said first leg to enter said recess, said aperture being laterally disaligned with respect to said recess for laterally flexing said leg to impose a substantial resistance to withdrawal thereof.

24. In a hair curling device, a curler member adapted to have a lock of hair wound thereon and a spread hair pin supported at one end thereof, with one leg of the pin impositively accommodated in said member and the other leg over the external surface of said member, said curler member having an aperture at one end thereof through which said first named hair pin leg is adapted to be inserted and an internal annular recess extending axially of said member for receiving the extremity of said first leg and disposing said extremity fixedly in said recess when operatively received thereby, said recess being spaced axially from said aperture and the walls of said recess being laterally disaligned with respect to said aperture for laterally flexing said leg to impose a substantial resistance to withdrawal thereof.

HARRY KLEIN.
